(57) **ABSTRACT**

A subassembly for a shaving razor cartridge with a base having a front wall with a top surface and a rear wall with a top surface. At least one blade is mounted to the base between the front wall and the rear wall. The at least one blade has a cutting edge positioned at least 0.5 mm below a plane tangent to the top surface of the front wall and the top surface of the rear wall.

FIG. 4

FIG. 5

1
RAZOR CARTRIDGE

This application is a divisional from U.S. application Ser. No. 16/841,375 which is now U.S. U.S. Pat. No. 11,794,363.

FIELD OF THE INVENTION

The present invention relates to wet safety razors and more particularly to shaving razor cartridges that have a housing for guarding the skin against contact from one or more blades.

BACKGROUND OF THE INVENTION

In general, a cartridge or blade unit of a safety razor has at least one blade with a cutting edge which is moved across the surface of the skin being shaved by means of a handle to which the cartridge is attached. Some shaving razors are provided with a spring biased cartridge that pivots relative to the handle to follow the contours of the skin during shaving. The cartridge may be mounted detachably on the handle to enable the cartridge to be replaced by a fresh cartridge when the blade sharpness has diminished to an unsatisfactory level, or it may be attached permanently to the handle with the intention that the entire razor be discarded when the blade or blades have become dulled. Razor cartridges usually include a guard which contacts the skin in front of the blade(s) and a cap for contacting the skin behind the blade(s) during shaving. The cap and guard may aid in establishing the so-called "shaving geometry", i.e., the parameters which determine the blade orientation and position relative to the skin during shaving, which in turn have a strong influence on the shaving performance and efficacy of the razor. The cap may comprise a water leachable shaving aid to reduce drag and improve comfort. The guard may be generally rigid, for example formed integrally with a frame or platform structure which provides a support for the blades. Guards may also comprise softer elastomeric materials to improve skin stretching.

In addition, covers have been developed that fit over shaving cartridges to facilitate cutting the hair to a specified length. These covers also guard the skin by raising the blades from the surface of the skin and thus limiting contact. However, since these covers are intended to be mounted over existing shaving razor cartridges that intended to shave the skin, the trimmer performance (i.e., cutting hair to length) of the cover is limited and not efficient. Thus, there is a need for a safety shaving razor that provides safe and efficient of cutting hair to a specified length.

SUMMARY OF THE INVENTION

In one aspect, the invention features, in general a subassembly for a shaving razor cartridge with a base having a front wall with a top surface and a rear wall with a top surface. At least one blade is mounted to the base between the front wall and the rear wall. The at least one blade has a cutting edge positioned at least 0.5 mm below a plane tangent to the top surface of the front wall and the top surface of the rear wall.

In another aspect, the invention features, in general a method of assembling a shaving razor cartridge by providing a base having a front wall with a top surface and a rear wall with a top surface. At least one blade having a cutting edge is mounted to the base between the front wall and the rear wall. The cutting edge is positioned at least 0.5 mm below

2

a plane tangent to the top surface of the front wall and the top surface of the rear wall. A cage having a plurality of ribs is mounted to the base.

In another aspect, the invention features, in general a shaving razor cartridge with a base having a front wall with a top surface. A cage is fixed to the base. The cage has an upper skin contacting surface with a plurality of ribs defining a plurality of open slots and a front face generally transverse to the upper skin contacting surface. The front face has a lower surface interconnecting a plurality of ribs that define a plurality of open slots extending into the front face and are communication with the open slots of the upper skin contacting surface. At least one blade is mounted to the base. The blade has a cutting edge positioned below the upper skin contacting surface and immediately behind the front wall. The lower surface of the front face is positioned a vertical distance below the cutting edge.

BRIEF DESCRIPTION OF THE DRAWINGS

Other features and advantages of the present invention, as well as the invention itself, can be more fully understood from the following description of the various embodiments, when read together with the accompanying drawings, in which:

FIG. 1A is a front perspective view of a shaving razor cartridge according to one possible embodiment of the present invention.

FIG. 1B is rear perspective view of the shaving razor cartridge of FIG. 1A.

FIG. 2 is an assembly view of the razor cartridge of FIGS. 1A and 1B.

FIG. 3 is a perspective view of a subassembly of the razor cartridge of FIGS. 1A and 1B.

FIG. 4 is a cross section view of the subassembly in an upright position, taken generally along the line 4-4 of FIG. 3.

FIG. 5 is a cross section view of the razor cartridge, taken generally along the line 5-5 of FIG. 1.

DETAILED DESCRIPTION OF THE INVENTION

Referring to FIGS. 1A and 1B, front and rear perspective views of a shaving razor cartridge are shown, respectively. The shaving razor cartridge 10 may be mounted to a handle (not shown).

The shaving razor cartridge 10 may be removable or permanently mounted to the handle. For example, the shaving razor cartridge 10 may be detachably mounted on a handle to enable the shaving razor cartridge 10 to be replaced by a fresh shaving razor cartridge 10 when the blade sharpness has diminished to an unsatisfactory level, or it may be attached permanently to the handle with the intention that the entire razor be discarded when the blade or blades have become dulled. The shaving razor cartridge 10 may include a housing 12. The housing 12 may be molded out of a polymeric material or manufactured from other materials, such as metal. The housing 12 may have an upper skin contacting surface 14 and a front face 16 that is transverse to the upper skin contacting surface 14. The upper skin contacting surface 14 may define a plurality of open slots 18 that are in communication with a plurality of corresponding open slots 20 defined by the front face 16. The open slots 18 may extend all the way to a rear face 40 (FIG. 1B). The open slots 20 may be defined and interconnected by a lower surface 21 of the front face. Accordingly,

when hairs contact the front face 16, they are directed immediately to the open slots 20 (i.e., the open slots 20 extend into the front face 16). The open slots 18 and 20 may be separated by corresponding ribs 22. The ribs 22 may extend continuously along the upper skin contacting surface 14 and down the front face 16. Accordingly, the front face may be defined by a plurality of ribs 22 and the lower surface 21 to form the open slots 20. The ribs may have a width "w1" of about 0.25 mm to about 5 mm and preferably about 0.4 mm to about 1 mm. The ribs 22 may be spaced apart (i.e., width of the slots 18 and 20) by about 0.25 mm to about 5.0 mm and preferably about 0.7 mm to about 0.8 mm. If the spacing between adjacent ribs is too great, the blades may shave the philtrum (the vertical indentation in the middle area of the upper lip) rather than cutting the hair to length (e.g., the philtrum may sag between the ribs 22). In certain embodiments, the width "w1" may be less than the distance between the ribs 22. As will be described in greater detail below, a ratio of the width to height of the ribs 22 should be sufficient to prevent the ribs 22 from breaking or deforming during use. Furthermore, the spacing of the ribs 22 (i.e., slot width) and the width of the ribs 22 may impact the efficiency of the blades to cut hair. For example, the width of the slots 18 and 20 should be large enough for hairs to pass through and the width of the ribs 22 should be large enough to provide sufficient strength without trapping a surplus of hairs. The dimensions of the ribs 22 may also prevent skin from sagging between the ribs 22 and contacting the skin during a shaving stroke.

As shown in FIG. 2, one or more blades 24a 24b and 24c may be mounted within the housing 12, as shown in FIG. 2. Each of the blades 24a 24b and 24c may have a corresponding cutting edge 26a 26b and 26c. The first blade 24a and first blade edge 26a may be immediately adjacent the ribs 22 of the front face 16. Although three blades 24a, 24b and 24c are shown, the razor cartridge 10 may have more or fewer blades 24 depending on the desired performance and cost of the razor cartridge 10. The open slots 18 and 20 may extend transverse to the cutting edges 26a 26b and 26c. The blades 24a 24b and 24c may be secured to the housing 12 with one or more clips 28a and 28b. The blades 24 may be fixed in the housing 12 or may be resiliently mounted such that the blade members 24, (e.g., respective cutting edges 26) are biased against the clips 28a and 28b. The clips 28a and 28b may aid in retaining the blades 24a, 24b and 24c in an up and down direction (i.e., toward and away from the upper skin contacting surface 14). The clips 28a and 28b may comprise a metal, such as aluminum, but plastic may also be used. The clips 28a and 28b may also be interconnected to form a one-piece assembly. Other assembly methods known to those skilled in the art may also be used to secure and/or mount the blades 24a, 24b and 24c to the housing 12 including, but not limited to, wire wrapping, cold forming, hot staking, insert molding, ultrasonic welding, and adhesives. As will be described in greater detail below, the ribs 22 may prevent the cutting edges 26a, 26b and 26c from contacting the skin during a stroke, so only hair is cut not skin.

Referring to FIG. 2, an assembly view of the shaving razor cartridge 10 is illustrated. In certain embodiments, the housing 12 may comprise a two-piece assembly. For example, the housing 12 may comprise a base 30 (e.g., a lower portion) and a cage 32 (e.g., an upper portion) that is mounted over the base 30. In certain embodiments, the base 30 may be permanently fixed to the cage 32. Accordingly, the cage 32 may define the upper skin contacting surface 14 and the blades 24a, 24b and 24c may be mounted to the base 30.

In certain embodiments, the cage 32 may secure the blades 24 within the base 30 (with or without the clips 28a and 28b). For example, the clips 28 may provide either a temporary or an extra measure of securement for the blades 24a, 24b and 24c.

The base 30 may have a front wall 34 and a rear wall 35 with respective top surfaces 36 and 37. The first blade edge 26a may be immediately behind the front wall 34 to facilitate the unobstructed passage of hair to the first blade edge 26a. One or more of the top surfaces 36 and 37 may be recessed relative to the cutting edges 26a, 26b and 26c. The top surfaces 36 and 37 may extend along a length "L1". It is understood that the front wall 34 and the rear wall 35 may have one or more projecting features to aid in securement of the base 30 to the cage 32. The top surfaces 36 and 37 may have one or more projecting features to aid in securement of the base 30 to the cage 32. The top surfaces 36 and 37 may extend between and positioned below the clips 28a and 28b. The top surface 36 being recessed may allow for an open area in front of the first blade edge 26a so hair is not trapped, as well as provide for an area on the housing for the clips 28a and 28b to rest above the top surface 36. For example, one or more of the top surfaces 36 and 37 may be recessed relative to the first cutting edge 26a by more than 0.20 mm, such that the top surface 36 and 37 do not interfere with or touch the skin, during trimming of hair. As will be explained in greater detail below, all of the blades 24a, 24b, and 24c may be mounted to the base 30 such that the cutting edges 26a, 26b and 26c are positioned above the top surface 36 along the length "L1". In certain embodiments, L1 may be about 17 mm to about 35 mm. Accordingly, all the cutting edges 26a, 26b and 26c are not protected by a guard and cap as traditional razor cartridges and thus all the shaving forces would be applied directly to the cutting edges 26a, 26b and 26c because the top surfaces 36 and 37 are recessed such that they do not act as a guard and cap to support (e.g., contact) the skin. However, the cage 32 may be mounted over the base 30 to prevent the cutting edges 26 from contacting the skin, thus resulting in a very safe shave by cutting the hairs to a pre-determined length. The clips 28a and 28b may be mounted to the base 30 prior to the cage 32 being mounted to the base 32. The cage 32 may define a pair of openings 38a and 38b dimensioned to receive the corresponding clips 28a and 28b. The cage 32 may be spaced apart from the clips 28a and 28b, to facilitate simple assembly. For example, the openings 38a and 38b may allow the clips 28a and 28b to be secured to the housing 12 either before or after the cage 32 is mounted to base 30. The openings 38a and 38b may allow the cage 32 to directly contact the cutting edges 26a, 26b and 26c by not resting on top of the clips 28a and 28b. In certain embodiments, the cage 32 would rest directly against the cutting edges 26a, 26b and 26c, thus potentially eliminating the need for the clips 28. Furthermore, hair and shaving debris may become trapped between the cage 32 and the cutting edge 26 if the cage 32 rested on top of the clips 28 and not the cutting edges 26a, 26b and 26c. The openings 38a and 38b may be enclosed and extend between the front face 16 and a rear face 40. As also shown in FIG. 1B, the rear face 40 may interconnect the ribs 22 at a rear of the housing 12 (e.g., cage 32) and lower surface 21 may interconnect the ribs 22 at a front of the housing 12 (cage 32) to reinforce the ribs 22.

Referring to FIG. 3, a subassembly 44 is shown which may be incorporated in the shaving razor cartridge of FIG. 1. The subassembly 44 may include the base 30, blades 24a, 24b and 24c and clips 28a and 28b. The blades 24a, 24b and 24c may be mounted to the base 30 between the front wall 34 and a rear wall 46. In certain embodiments, the length "L1" of the top surface 36 of the front wall 34 may be at least

90% of an overall length “L2” of the blades **24a**, **24b** and **24c** that are exposed (e.g., distances between the clips **28a** and **28b**). The top surface **36** may be bounded on lateral ends **48** and **50** by retaining walls **52** and **54**. The retaining walls **52** and **54** may extend above the top surface **36** to facilitate the positioning and securement of the clips **28a** and **28b** to the base **30**. For example, each clip **28a** and **28b** may be positioned between one of the retaining walls **52** and **54** and a corresponding lateral wall **56** and **58**.

Referring to FIG. 4, a cross section view of the subassembly **44**, taken generally along the line **4-4** of FIG. 3 is illustrated. The top surface **36** on the front wall **34** of the base **30** may be positioned a vertical distance of at least 0.5 mm below the cutting edges **26a**, **26b** and **26c** (e.g., a cutting plane **64**). In certain embodiments, the vertical distance **d1** may be about 0.5 mm to about 5 mm. The position of the top surface **36** may allow the hair to reposition itself in a more upright position as hair is cut (e.g., by the first cutting edge **26a**). For example, the top surface **36** may push down and trap long hairs in front of the blades **24**, if the top surface **36** was positioned too close to the cutting plane **64** (or the first cutting edge **26a**), thus negatively impacting cutting efficiency, especially for longer hairs that tend to lay flat on the skin. One or more of the cutting edges **26a**, **26b** and **26c** may be positioned a vertical distance “**d2**” above a plane **P1** tangent to the top surface **36** of the front wall **34** and a top surface **37** of the rear wall **46**. The distance **d2** may be greatest at the first cutting edge **26a** closest to the front wall **34** and the least closest to the rear wall **46**. It is believed, without being held to theory, that increasing **d2** closer to the front wall **34** improves cutting efficiency. After the hair is trimmed by the first cutting edge **26a**, it is less likely to lay flat because it is shorter, thus **d2** may be less at the second cutting edge **26b** and even less at the cutting edge **26c** closest to the rear wall **46**. In certain embodiments, **d2** may be about 0.5 mm to about 3 mm as measured at any of the cutting edges **26a**, **26b** and **26c**.

The shaving efficiency of the shaving razor cartridge **10** (FIG. 1) may be enhanced by improving rinsability. Traditional shaving razor cartridges rely on smaller distances between cutting edges or intermediate guards between adjacent blades for improved comfort because pressure is distributed between the cutting edges **26a**, **26b** and **26c**. However, the ribs **22** (FIG. 1) absorb all of the pressure from the skin, not the cutting edges **26a** **26b** and **26c**, which allows the cutting edges **26a** **26b** and **26c** to be spaced further apart from each other. In certain embodiments, distances “**d3**” and “**d4**” between a pair of immediately adjacent cutting edges **26a**, **26b** and **26c** may be greater than 1.75 mm, for example, about 1.8 mm to about 2.0 mm, or about 2.0 mm to about 2.5 mm, which may allow for even more effective rinsing by providing an open gap (as best seen in FIG. 3) between immediate cutting edges **26a**, **26b** and **26c**, without sacrificing trimming efficiency or comfort.

Referring to FIG. 5, a cross section view of the shaving razor cartridge **10**, taken generally along the line **4-4** of FIG. 1 is illustrated. The cage **32** may be mounted to the sub-assembly **44** (i.e., the base **30**). The housing **12** (e.g., the base **30** and the cage **32**) may allow for hair to freely pass through the slots **20** (FIG. 1) of the front face **16**. The upper skin contacting surface **14** and the front face **16** may intersect at an exterior angle “**A1**” that is less than 90 degrees, for example, about 45 degrees to about 85 degrees to facilitate the passage of hair through the slots **20** (FIG. 1) of the front face **16**. The intersection of the front face **16** and the upper skin contacting surface **14** may form a radius **R1** of the ribs **22**. In certain embodiments, **R1** may be about 0.1

to about 3 mm and preferably about 0.25 mm to about 1 mm. The lower surface **21** may be positioned a vertical distance “**d5**” of at least 0.5 mm below the cutting edges **26a**, **26b** and **26c** (e.g., about 0.5 mm to about 3 mm). The rear face **40** may have a top surface **60** extending between the ribs **22** (see also FIG. 1B) that is positioned a vertical distance “**d6**” below the cutting edges **26a**, **26b** and **26c**, which may help release the hairs freely (i.e., prevent from hairs being flattened down during a shaving stroke), thus allowing for more efficient trimming of hair.

The upper skin contacting surface **14** may have an opposing interior surface **62** (e.g., height of the ribs **22**). The length of the hair left after trimming with the shaving razor cartridge **10** may be determined by a vertical distance “**d8**” measured from the upper skin contacting surface **14** to the opposing interior surface **62** (e.g., if the cutting edges **26a**, **26b**, **26c** are in contact with the opposing interior surface **62**). It is understood that the cutting edges **26a**, **26b**, **26c** may contact or be spaced apart from the opposing interior surface **62**. The vertical distance “**d8**” may be about 0.5 mm to about 5 mm and more preferably about 1 mm to about 2.5 mm. If **d8** is too small, skin may bulge between the ribs **22** and contact the skin, thus cutting the hair too short. Furthermore, hair longer than 5 mm tends to lay flat and thus will not be cut if **d8** is greater than 5 mm.

It is believed, without being held to theory, that increasing the vertical distance **d5** and **d6** improves cutting efficacy by minimizing interference of the hair before it is cut by the first cutting edge **26a** (for **d5**) after it is cut by the last cutting edge **26c** (for **d6**). Accordingly, the exposure of the blade edges **26a**, **26b** and **26c** may be determined by **d8** (e.g., the height of the ribs **22**) and not a feature such as a guard in front of the blades that can push hairs down against the skin making them more difficult to trim. Guards contacting the skin do not present such an issue for typical shaving razors because the cutting edges are contacting and shaving the skin (i.e., cutting hair at or below skin level). Accordingly, the blade edges are able to contact and cut the hairs that may lay flat, lift them up and cut them. However, cutting the hairs above skin level is more difficult because the cutting edges may not be able to reach hairs that lay flat. Accordingly, the housing **12** may define a horizontal gap **66** extending from the first cutting edge **26a** to a front interior face **68**, opposing the front face **16**. In certain embodiments, the horizontal gap **66** may be about 0.5 mm to about 3.0 mm and preferably about 1 mm to about 2 mm. The gap **66** may allow for improved rinsing and allow longer trimmed hairs to rinse out through the housing **12**. The gap **66** may also allow for hairs to release and be presented to the first cutting edge **26a** in a more upright position. The front wall **34** and top surface **36** may be recessed and thus not extend into the gap **66**. It is understood that the lateral end walls **52** and **54** (FIG. 3) are positioned laterally of the bottom surface **36** and thus also does not extend into the gap **66**.

The positioning of the ribs **22** (FIGS. 1A and 1B) over the cutting edges **26a**, **26b** and **26c** helps prevent the skin from contacting the cutting edges **26a**, **26b** and **26c** and eliminates the need of a guard bar in front of the cutting edges **26a**, **26b** and **26c** to support the skin. For example, the height and the spacing of the ribs **22** may prevent skin from bulging between the ribs and contacting the cutting edges **26a**, **26b** and **26c**. Furthermore, the ribs **22** (FIGS. 1A and 1B) may also allow the cutting edges **26a**, **26b** and **26c** to be spaced further apart from each other because the cutting edges **26a**, **26b** and **26c** do not exert pressure against the skin.

The dimensions and values disclosed herein are not to be understood as being strictly limited to the exact numerical

values recited. The term "about" should be interpreted herein as within typical manufacturing tolerances.

Every document cited herein, including any cross referenced or related patent or application and any patent application or patent to which this application claims priority or benefit thereof, is hereby incorporated herein by reference in its entirety unless expressly excluded or otherwise limited. The citation of any document is not an admission that it is prior art with respect to any invention disclosed or claimed herein or that it alone, or in any combination with any other reference or references, teaches, suggests or discloses any such invention. Further, to the extent that any meaning or definition of a term in this document conflicts with any meaning or definition of the same term in a document incorporated by reference, the meaning or definition assigned to that term in this document shall govern.

While particular embodiments of the present invention have been illustrated and described, it would be obvious to those skilled in the art that various other changes and modifications can be made without departing from the spirit and scope of the invention. It is therefore intended to cover in the appended claims all such changes and modifications that are within the scope of this invention.

What is claimed is:

1. A subassembly in an upright position for a shaving razor cartridge comprising:
a base having a front wall with a top surface and a rear wall with a top surface;
at least one blade being mounted to the base between the front wall and the rear wall, the at least one blade having a cutting edge;
a cage mounted over the base, the cage having a front face defined by a plurality of ribs and a lower surface defining a plurality of open slots, wherein the front face of the cage is positioned in front of the front wall of the base to direct hair to the open slots,
wherein the cutting edge is positioned at least 0.5 mm above a plane tangent to the top surface of the front wall and the top surface of the rear wall.
2. The subassembly of claim 1 wherein the lower surface is positioned a vertical distance of at least 0.5 mm below the cutting edge.
3. The subassembly of claim 2 wherein the cage has a rear face with a top surface extending between the ribs that is positioned a vertical distance below the cutting edge.
